Application filed March 7, 1922. Serial No. 1,067. Term of patent 14 years.

To all whom it may concern:

Be it known that I, HAROLD E. NOCK, a citizen of the United States, residing at Newburyport, in the county of Essex and State of Massachusetts, have invented a new, original, and ornamental Design for a Spoon or Analogous Article, of which the following is a specification, reference being had to the accompanying drawing, forming a part thereof.

In the accompanying drawing Figure 1 is a view of the front of a spoon showing my new design, Fig. 2 is a view showing the de-

sign in section at the line 2—2 of Fig. 1; and Fig. 3 is a view similar to Fig. 2 at the line 3—3 of Fig. 1. It will be understood from the delineation of the drawing that my invention resides in the conformation of the front face of the spoon or analogous article.

It will be understood that the shape or outline of the handle is not novel.

Having thus described my invention, I claim:

The ornamental design for a spoon or analogous article, as shown.
